(57) **CLAIM**

(22) Filed: **Dec. 1, 2022**

The ornamental design for a valve core with valve seat for a faucet as shown and described.

(51) LOC (15) Cl. 23-01

DESCRIPTION

(52) U.S. Cl.

USPC **D23/249**

(58) **Field of Classification Search**

USPC D23/233, 303, 269, 249

FIG. 1 is a front perspective view of a valve core with valve seat for a faucet showing my new design;

CPC F16K 3/0227; F16K 1/46; F16K 5/0673;

FIG. 2 is a front view thereof;

F16K 1/2263; F16K 41/04; F16K 3/243;

FIG. 3 is a rear view thereof;

F16K 5/0663; F16K 5/0464; F16K 15/16;

FIG. 4 is a side view thereof;

F16K 15/08; F16K 15/10; F16K 1/42;

FIG. 5 is an opposite side view thereof;

F16K 25/005; F16K 15/148

FIG. 6 is a top plan view thereof;

See application file for complete search history.

FIG. 7 is a bottom plan view thereof;

(56) **References Cited**

FIG. 8 is a cross sectional view thereof; and,

U.S. PATENT DOCUMENTS

FIG. 9 is a rear perspective view thereof.

D252,701 S * 8/1979 Caldwell D23/249
